UNITED STATES PATENT OFFICE

121,130

DESIGN FOR A DISPLAY RACK OR SIMILAR ARTICLE

Lee A. Shelton, Des Moines, Iowa, assignor to
New Monarch Machine & Stamping Co., Des Moines, Iowa

Application January 29, 1940, Serial No. 89,858

Term of patent 7 years

To all whom it may concern:

Be it known that I, Lee A. Shelton, a citizen of the United States and resident of Des Moines, Polk County, Iowa, have invented a new, original, and ornamental Design for a Display Rack or Similar Article, of which the following is a specification, reference being had to the accompanying drawing, forming a part thereof.

Fig. 1 is a front elevational view of the display rack or similar article, showing my design;

Fig. 2 is a top plan view;

Fig. 3 is a side elevational view; and
Fig. 4 is a front perspective view thereof, on an enlarged scale.

The rear of the display rack is plain.

I claim:

The ornamental design for a display rack or similar article, substantially as shown and described.

LEE A. SHELTON.
